REFINING & CHEMICAL COMPANY, OF CLEVELAND, OHIO, A CORPORATION
OF OHIO.

PUMP FOR RECEPTACLES.

1,317,483.

Specification of Letters Patent. Patented Sept. 30, 1919.

Application filed October 21, 1918. Serial No. 258,946.

To all whom it may concern:

Be it known that I, EDSON L. CANNON, a citizen of the United States, residing at Cleveland Heights, in the county of Cuyahoga and State of Ohio, have invented a certain new and useful Improvement in Pumps for Receptacles, of which the following is a full, clear, and exact description, reference being had to the accompanying drawings.

10 This invention relates to devices for dispensing liquids, and more particularly to pumps which are so constructed as to enable them to be conveniently applied to barrels or similar receptacles for the purpose of removing the contents therefrom.

While the invention is capable of use in connection with other receptacles and for the purpose of dispensing other liquids, it is particularly well adapted for dispensing 20 grease from barrels, and in measured quantities; and it is the general object of the invention to provide a device of the character referred to which is capable of being conveniently and quickly applied to and removed from a barrel or like receptacle. A further object of the invention is to provide a device of this character which is simple of construction, comparatively inexpensive of production, and which will efficiently perform the dispensing operation, particularly in connection with the handling of viscous substances, such as grease. Further and more limited objects of the invention will appear in the detailed description 30 embodied in the specification.

In the drawings forming part hereof, Figure 1 represents a vertical sectional view through a barrel having applied thereto a device constructed in accordance with my invention, said device being shown in elevation; Fig. 2 a central vertical section through the said device, corresponding to the line 2—2 of Fig. 1; Fig. 3 an enlarged sectional detail corresponding to the line 3—3 of Fig. 45 2; and Fig. 4 a similar detail corresponding to line 4—4 of Fig. 2.

Describing the various parts illustrated by means of reference characters, 1 denotes a receptacle, shown as a barrel having a lower head 2 and an upper head 3. The last mentioned head is provided with an aperture 4 for the reception of certain parts of the pump structure which are to be mounted within the barrel.

55 On top of the upper head 3 is a support-

ing base comprising an elongated plate 5 having a disk portion 6 adapted to cover the aperture 4, the plate being secured to the top of the barrel, as by means of screws 7. The plate extends from the central portion of the barrel toward the chime 8, where it is provided with a pair of upwardly extending lugs 9 between the upper ends of which is pivoted one end of the pump handle lever 10, the pivotal connection being indicated at 11. 60 The parts 5, 6 and 9 may be made as a casting and the disk 6 is provided with a pair of upwardly extending hollow projections or bosses 12 and 13, each projection being provided with a set screw, one of which is indicated at 14. The central portion of the disk 6 is provided with an aperture 6^a, intermediate the projections 12 and 13 for a purpose to be described hereinafter.

The pump which is shown herein as employed in conjunction with the foregoing parts will now be described. 15 denotes a cap member, which may be conveniently made as a casting comprising a central plate 16 having a depending circular skirt or flange 17 and hollow lugs 18 and 19 on opposite sides of such central plate. When the pump is assembled, these lugs and the openings therethrough will align respectively with the projections 12 and 13 and the openings therethrough. Each lug 18, 19 is provided with a set screw, one of which is indicated at 19^a.

Beneath the cap member 15 is a casing member 20, which may also be formed as a casting, said casing member having in the bottom wall 21 thereof an inlet opening 22 controlled by an inwardly opening valve 23 pivoted at one side of said opening 22, as by means of a rod 24 extending through a pivot lug 25 on the valve and mounted in the walls of the casing member. Above the bottom plate 21 is a chamber 26. The top of the chamber is provided with a cover portion 27 provided with cylindrical seats 28 and 29 90 alining respectively with the aperture through the lug 19 and with the downwardly extending circular flange 17. Both of the seats 28 and 29 are located above the chamber 26, the seat 29 being directly above the aperture 22 and valve 23. At one side of the chamber 26, the casing member 20 is provided with an extension 30 having a cylindrical seat 31 in alinement with the aperture through the lug 18 thereabove. From 95 100 105 110

the bottom 21 of the casing member a pair of feet 32 extend downwardly, said feet serving to support the pump assembly upon the lower head 2 of the barrel and permit the 5 access of grease to the chamber 26 through the valve 22.

33 denotes a pump cylinder which is secured within the flange 17 and the seat 29. Within this cylinder is the piston 34 the 10 operating or plunger rod 35 for which extends through the apertures 16, 4 and 15, the upper end of the rod being secured to a connecting member 36 which is slidably mounted upon a guide rod 37 extending from above 15 the head 3 through the hollow projections 12 and 18, with its lower end secured within the seat 31. A delivery pipe 38 extends through the hollow projections 13 and 19 and is secured at its lower end within the seat 28. 20 By means of the set screws 14 and 19^a, the guide rod 37 and the delivery pipe 38 may be secured firmly to the disk 6 and the cap member 15, the securing means also serving to anchor the pump proper within the barrel. 25 The delivery pipe 38 is shown as provided with an elbow 39 from which there extends a delivery connection 40.

The connection 36 is provided with a slot 41, located between the top and bottom 30 thereof and the lateral portions coöperating with the rods 35 and 37. The top and bottom portions of the slot walls are rounded, as shown at 42, whereby the handle lever 10 may slide along such walls without binding 35 during the pumping operation. The connecting member 36 is shown as secured to the plunger 35 by means of set screws 43.

The pump assembly comprising the parts 5-43 inclusive may be applied to a barrel 40 with the parts arranged as shown herein, the plate 5 and the connecting member 36 being adjustable whereby the assembly may be applied to barrels of varying depth.

With the parts constructed and arranged 45 as described, it is believed that the operation will be readily understood. On the lifting stroke of the handle lever 10 the piston 34 is elevated, thereby drawing in the grease or other material through the valve 23 until the cylinder 33 is filled. By depressing 50 the handle lever the valve 23 will be closed and an amount of grease or other liquid equal to the contents of the cylinder will be expelled through the pipe 38, the plunger rod 35 and the handle lever being maintained in operative relation to the other parts of the pump by means of the sliding connecting member 36 traveling upon the rod 37. Through the construction described, 55 the various parts of the pump are rigidly supported in position; the pump operates efficiently for the purposes for which it is designed; and the construction, while markedly efficient, comprises a minimum number 60 of parts.

It will be noted that the cap member for the cylinder 33 is detachably secured upon the cylinder through the delivery pipe 38 and the rod 37, being slidably mounted upon said rod and pipe; also that the pipe 38 and rod 37 are secured to the plate 5, thereby anchoring the pump within the barrel and preferably with the feet 32 bearing against the lower head. The plate 5 supports not only the pipe 38 and rod 37, but 75 also supports the plunger operating means and provides a guide through which the plunger rod may reciprocate.

Having thus described my invention, what I claim is:

1. The combination, with a receptacle having an upper and a lower head, of a pump comprising a casing and means for supporting the latter on the lower of said heads, inside said receptacle, a pump cylinder extending upwardly from said casing, a delivery pipe also extending upwardly from said casing, a guide rod extending upwardly from said casing, an inwardly opening valve in said casing, a cap for the upper end of said cylinder, said cap having lateral extensions through which said delivery pipe and said guide rod extend and a central opening, a plunger rod extending through said central opening, a plate supported on the upper head of said receptacle, said plate having apertures through which said delivery pipe and said guide rod extend and an aperture through which the plunger rod extends, a pivotal support carried by said plate, a pump lever connected to said support, and a connecting member having a central slot through which the plunger rod is connected, said connecting member being 100 slidably mounted on said guide rod.

2. The combination, with a receptacle having an upper and a lower head, of a pump casing adapted to be supported within the receptacle and upon the lower head, said casing having an inwardly opening valve, a cylinder extending upwardly from said casing, a piston in said cylinder, a delivery pipe extending from said casing, a guide rod also extending upwardly from said casing, a cap member closing the upper end of said cylinder and having an opening therethrough for the plunger rod and provided with means for securing the same to the delivery tube and the guide rod, a pump lever, means pivotally supporting the same above the upper head of said receptacle, means connecting the plunger rod and the pump lever, and means slidably supporting the pump lever on the guide rod.

3. The combination, with a receptacle having an upper and a lower head, a supporting plate or base secured to the upper surface of the upper head and having upwardly extending hollow lugs thereon and an aperture interposed between said lugs, a casing 130

adapted to be supported by the lower head of said receptacle, a cylinder extending upwardly from said casing, a delivery pipe and a guide rod extending upwardly from said casing and through the said hollow lugs, means for securing the said pipe and rod to their respective lugs, a piston in said cylinder, a plunger rod connected to said piston and extending through said aperture, a pump lever, means for pivotally supporting the same above the upper head, a connecting member slidably mounted upon the guide rod and connected to the plunger rod, and means connecting said member and said pump lever.

4. The combination, with a receptacle having an upper and a lower head, of a pump comprising a casing having a support adapted to rest on the lower of said heads, inside said receptacle, a pump cylinder extending upwardly from said casing, a delivery pipe also extending upwardly from said casing, an inwardly opening valve in said casing below said cylinder, a supporting plate on the upper head of said receptacle, a pump lever pivoted to said plate, a plunger rod extending through said plate, a guide rod extending upwardly from said plate, and a connection between said rod and said pump lever, said connection being slidably mounted on said guide rod and said delivery tube being secured to said plate.

5. The combination, with a receptacle having an upper and a lower head, of a pump comprising a casing having feet adapted to rest on the lower of said heads, inside said receptacle, a pump cylinder extending upwardly from said casing, a delivery pipe also extending upwardly from said casing, an inwardly opening valve in said casing below said cylinder, a guide rod extending upwardly from said casing, a supporting plate on the upper head of said receptacle, a pump lever pivoted to said plate, a plunger rod extending through said plate, and a connection between said rod and said lever, said connection being slidably mounted on said guide rod and said guide rod and delivery tube extending through and above said plate.

50 6. The combination, with a receptacle having an upper and a lower head, of a pump comprising a casing having means for supporting the same on the lower of said heads, inside said receptacle, a pump cylinder extending upwardly from said casing, a delivery pipe also extending upwardly from said casing, a valve opening inwardly into said casing, a guide rod extending upwardly from said casing, a cap closing the upper end of said cylinder and provided with means for connecting the same to said pipe and rod, a plunger rod extending through said cover plate, a pump lever, means pivotally supporting the same above the upper head of said receptacle, a connecting member slidably

mounted on said guide rod above the upper head of said receptacle, a connection between said member and said pump lever, and a connection between said member and said plunger rod.

7. The combination, with a receptacle having an upper and a lower head, of a pump comprising a casing adapted to be supported on the lower head, inside said receptacle, a delivery pipe extending from said casing, a cylinder extending upwardly from said casing, an inwardly opening valve in said casing, a plunger rod extending from said cylinder through the upper head, a guide rod extending upwardly from the upper head parallel with said plunger rod, a pump lever pivotally supported above the upper head, and a connecting member to which said pump lever and said plunger rod are connected, said member being slidably mounted upon the guide rod.

8. In a pump of the character described, the combination of a casing, an inwardly opening valve therein, a cylinder extending therefrom, a delivery pipe also extending from said casing, a cap member for said cylinder having openings therethrough, a piston in said cylinder, a plunger rod connected with said piston, said rod and said delivery pipe extending through said openings, a pump lever, a connection between said lever and said plunger rod, a guide rod, and means slidably supporting the pump lever on said guide rod.

9. In a pump of the character described, the combination of a casing, a pump cylinder extending upwardly from said casing, a delivery pipe also extending upwardly from said casing, a valve opening inwardly into said casing, a guide rod extending upwardly from said casing, a cap closing the upper end of said cylinder and provided with means for securing the same to said pipe and rod, a plunger rod extending through said cap, a plate, a pump lever, means pivotally supporting the same from said plate, a connecting member slidably mounted on said guide rod above said plate, a connection between said member and said pump lever, and a connection between said member and said plunger rod.

10. In a pump of the character described, the combination of a casing, a pump cylinder extending upwardly from said casing, a delivery pipe also extending upwardly from said casing, a guide rod extending upwardly from said casing, an inwardly opening valve in said casing, a cap for the upper end of said cylinder, said cap having means for securing the same to said delivery pipe and said guide rod, a plunger rod extending through said cap, a second plate above said cap and to which said guide rod and said delivery pipe are secured, a pivotal support carried by said plate, a pump lever con-

nected to said support, a member above the second plate slidably mounted on the guide rod and connected to the plunger rod, and a connection between said member and said 5 pump lever.

11. The combination, with a receptacle having an upper and a lower head, of a pump casing having an inwardly opening valve in the bottom thereof, a cylinder projecting upwardly from said casing, a delivery pipe and a rod also projecting upwardly from said casing, a cap for the upper end of said cylinder and slidably mounted upon said rod and delivery pipe, 10 the upper head having an opening therethrough and a plate covering said opening and through which the said pipe and rod extend and to which they are secured thereby to anchor the pump casing within said receptacle, a pump operating device also supported by said plate, and a plunger rod extending through said plate and connected to said device and having a plunger or piston within said cylinder.

12. The combination, with a receptacle, of a pump casing having an inwardly opening valve therein, a cylinder projecting from said casing, a delivery pipe and a rod also projecting from said casing, a cap for said cylinder having extensions through which said rod and delivery pipe extend, the said pipe and rod extending through a wall of said receptacle and the rod being operatively secured to said wall thereby to anchor the 30 pump casing within said receptacle, a pump operating device, and a plunger rod extending through said wall and connected to said device and having a plunger or piston within said cylinder.

13. The combination, with a receptacle having a lower head, of a pump casing having one or more feet adapted to engage the lower head and an inwardly opening valve in the bottom thereof, a delivery pipe and a cylinder projecting upwardly from and communicating with said casing, an anchoring rod secured to said casing and projecting upwardly therefrom, said rod and pipe extending through the upper head and said 45 rod being operatively secured to such head thereby to anchor the pump casing within the receptacle, a plunger rod extending through the upper head and having a piston or plunger within said cylinder, and a de-

vice for operating said rod also supported by 55 the upper head.

14. The combination, with a receptacle having an upper head provided with an opening and a lower head, of a pump casing having an inwardly opening valve in the bottom thereof, a delivery pipe and a cylinder projecting upwardly from and communicating with said casing, an anchoring rod secured to one side of said casing and projecting upwardly therefrom, a cap for 60 the upper end of the cylinder having extensions through which the said pipe and rod extend, said pipe and rod extending through the said plate and being secured thereto, a plunger rod extending through 70 the said cap and an opening in said plate and having a piston or plunger at its lower end within said cylinder, an upwardly projecting support on said plate, and means connected to said support for operating said 75 plunger rod.

15. A pump for receptacles comprising a casing having an inwardly opening valve therein, a delivery pipe and a cylinder projecting from and communicating with said casing, an anchoring rod secured to said casing and projecting therefrom, a plate adapted to be applied to an outer wall of such receptacle and to which said pipe and rod are secured thereby to anchor the pump 80 casing within the receptacle, a plunger rod extending through said plate and having a piston or plunger within said cylinder, and operating means for said plunger rod 85 adapted to be supported by said plate.

16. A pump for receptacles comprising a casing having an inwardly opening valve therein, a delivery pipe and a cylinder projecting from and communicating with said casing, an anchoring rod secured to one side 95 of said casing and projecting therefrom, a cap for the cylinder, a plate adapted to be applied to an outer wall of such receptacle, said rod extending through the said plate and being secured thereto, a plunger rod 100 extending through the said cap and having a piston or plunger at its lower end within said cylinder, and means for operating said plunger rod.

In testimony whereof, I hereunto affix my 105 signature.

EDSON L. CANNON.
